W. M. ADAMS & J. D. RENICK.
AUXILIARY HEATER.
APPLICATION FILED MAR. 26, 1915.

1,177,078.

Patented Mar. 28, 1916.

UNITED STATES PATENT OFFICE.

WILLIAM M. ADAMS AND JOSEPH D. RENICK, OF LORAIN, OHIO; SAID RENICK
ASSIGNOR TO SAID ADAMS.

AUXILIARY HEATER.

1,177,078.

Specification of Letters Patent. Patented Mar. 28, 1916.

Application filed March 26, 1915. Serial No. 17,221.

To all whom it may concern:

Be it known that we, WILLIAM M. ADAMS and JOSEPH D. RENICK, citizens of the United States, residing at Lorain, in the 5 county of Lorain and State of Ohio, have invented certain new and useful Improvements in Auxiliary Heaters, of which the following is a specification.

In heating systems utilizing hot air, places 10 remotely situated from the furnace are not generally heated satisfactorily, this being due primarily to the cooling of the hot air before it escapes from the register or outlet.

The present invention provides for the re-heating of the hot air in its travel at a point between the furnace and the outlet, thereby insuring satisfactory heating of the room, hall or other place to be kept warm.

The invention consists of a heater disposed 15 in the length of the hot air pipe for raising the temperature of the hot air in its passage through the pipe, such heater being supplementary in nature and utilized at such times only when the ordinary hot air furnace is 20 insufficient to perform the desired work.

This auxiliary heater may be utilized independently of the furnace in mild weather for heating.

A further purpose of the invention is the 25 formation of a heater which may be readily disposed in the length of a hot air pipe to be used in conjunction with the hot air furnace or independently thereof according to existing conditions and the requirements to 30 be met.

With these and other objects in view, which will readily appear as the nature of the invention is better understood, the same 35 consists in the improved construction and 40 novel arrangement and combination of parts which will be hereinafter fully described and particularly claimed.

In the accompanying drawings has been 45 illustrated a simple and preferred form of the invention, it being, however, understood that no limitation is necessarily made to the precise structural details therein exhibited, but that changes, alterations and modifications within the scope of the invention as 50 claimed may be resorted to when desired.

Referring to the drawings, —Figure 1 is a vertical central longitudinal section of a heater embodying the invention showing the same disposed in the length of a hot air 55 pipe; Fig. 2 is a transverse section on the

line 2—2 of Fig. 1, looking to the left as indicated by the arrows; Fig. 3 is a cross section on the line 3—3 of Fig. 1, looking to the left as designated by the arrows.

Corresponding and like parts are referred 60 to in the following description and indicated in all the views of the drawings by the same reference characters.

The heater in its general formation embodies a body portion and heads or end 65 pieces. The body portion of the heater is hollow and comprising an outer casing 1 and an inner casing 2. The casings 1 and 2 are spaced apart and have a concentric relation so as to provide a uniform space between 70 them. To conserve heat the outer casing 1 is preferably formed of a hollow wall or spaced shells inclosing a filling of asbestos or other refractory material. The inner casing 2 is preferably of sheet metal and of 75 a single thickness to provide for a ready transfer of the heat. The heads or end pieces 3 are of annular form and are provided with flanges at their inner and outer edges for retaining the parts in place. The 80 outer flange 4 of each end piece faces inward so as to engage the adjacent end of the casing 1. The flange at the inner edge of each end piece projects in opposite directions, as indicated at 5 and 6, the flanges 5 facing 85 inward engage the ends of the casing 2 whereas the flanges 6 facing outward receive the ends of the hot air pipe 7 making connection with the ends of the heater. The flanges 4 and 5 retain the casings 1 and 2 in 90 proper position and insure close joints. Tie rods 8 connect the heads or end pieces 3 and retain the several parts 1, 2 and 3 in proper position. The tie rods 8 are preferably located exterior to the body of the heater and 95 pass through openings formed in ears projecting outward from the end pieces.

Longitudinal partitions 9 divide the space between the casings 1 and 2 so as to form an upper compartment 10 and a lower compartment 11. The partitions 9 are oppositely disposed and extend the entire length of the body of the heater. A pipe 12 extends through the casing 2 and its end portions 13 and 14 project in opposite directions and connect with opposite ends of the compartments 10 and 11. The pipe 12 is preferably disposed in the center of the casing 2 and the end 13 projects upwardly and attaches to one end of the casing 2 and communicates 110

with an end portion of the compartment or space 10. The end portion 14 projects downwardly and connects with the opposite end portion of the casing 2 and communicates with the opposite end of the compartment 11. The arrangement of the pipe 12 insures a positive circulation of the hot air and gases of the auxiliary heater through the compartments 10 and 11.

10 A burner A is located at one end of the body and communicates with the space or compartment 10 at one end thereof. An outlet pipe B connects with the opposite end of the body of the heater and communicates with the space or compartment 11 at a point opposite the burner A. While the burner A may be of any construction it is shown as consisting of a mixing chamber 15 and a burner tube 16, such mixing chamber having an opening in a side which is controlled by means of a slide 17 whereby the burner may be lighted when required. A protecting plate 18 is attached to the casing 2 opposite the burner and prevents the burning out 25 of the casing at this point. The outlet pipe B may connect with a chimney or extend to any convenient point for discharging the gases resulting from the burner A when the heater is in service.

30 When a heater embodying the invention is installed, a section of the hot air pipe 7 corresponding to the length of the heater is removed and is replaced by the heater. The inner diameter of the casing 2 preferably corresponds to the diameter of the hot air pipe 7 so as not to interfere with the ordinary passage of the hot air through the pipe 7. In mild weather when the furnace is sufficient to heat all places connected therewith the heater is not utilized but when the furnace is insufficient to heat the hall, room or other place, the burner attached to the auxiliary heater located in the length of the hot air pipe 7 connecting such hall with the furnace, is lighted. The flame of the burner together with the hot air and gases resulting therefrom pass through the space formed between the two casings 1 and 2, such hot air and gases passing through the 45 compartment 10 from one end to the opposite end thereof, hence through the pipe 12 to one end of the compartment 11 and thence through such compartment 11 to the opposite end thereof and out through the pipe B.

50 The walls of the casing 2 and pipe 12 are heated to a high temperature and the heat radiated from such walls is taken up by the air traveling through the hot air pipe 7 and the inner casing 2 of the heater, thereby heating the air and insuring a proper warming of the place to be heated. It is to be understood that when the furnace is not running the auxiliary heater may be utilized for warming the air passing through the 60 pipe 7 so as to heat the place with which

the hot air pipe 7 is connected and thus it will be understood that the heater may be utilized either as a supplementary heater or as a primary heater.

Having thus described the invention, what is claimed as new is:—

1. A heater of the character specified comprising spaced inner and outer casings having the space formed between them closed at opposite ends, partitions dividing the space between the casings to form independent longitudinal compartments, a heating device connected with one of the compartments, an outlet pipe having connection with one of said compartments for carrying off the gases formed by the heating device, and a pipe extending longitudinally through the inner casing and having its opposite ends connected with and forming the sole source of communication between said compartments. 80

2. A heater of the character specified comprising spaced inner and outer casings and having the space formed between such casings closed at opposite ends, longitudinal partitions dividing the space between the casings into compartments, a heating device in communication with an end of one of said compartments, an outlet pipe in communication with the opposite end of the other compartment, and a pipe passing through the inner casing and connected at one end with one of said compartments at the end remote from the heating device and with the other compartment at the end remote from the outlet pipe. 90

3. A heater of the character specified comprising inner and outer casings having the space formed between them closed at opposite ends, the inner casing being open throughout its length for the free circulation of air therethrough, a burner connected with the outer casing near one end thereof, an outlet pipe connected with the outer casing near the opposite end thereof, and a pipe passing through the inner casing and having one end connected with the inner casing remote from the burner and having its opposite end connected with the opposite end of the inner casing remote from the outlet pipe. 100

4. A heater of the character described comprising inner and outer casings, annular end pieces closing the space formed between the casings and having inner flanges to engage the ends of the casings to hold them in proper position and to insure the formation of close joints, said end pieces having outwardly extending flanges longitudinal partitions dividing the space between the casings into independent compartments, a heating device having connection with one compartment near one end of the outer casing, an outlet pipe having connection with the other compartment at the 110 115 120 125 130

- opposite end of said outer casing, and a pipe passing through the inner casing and having its opposite ends connected with opposite ends of the inner casing to insure a positive circulation of the hot air through the space formed between the two casings.
5. A heater comprising spaced inner and outer casings having the space formed between them closed at opposite ends, the inner casing being adapted to have air passed therethrough, a burner connected with an end portion of the outer casing and disposed at substantially right angles thereto, an outlet pipe connected with the opposite end of the outer casing, a pipe extending longitudinally through the inner casing and having its opposite ends connected with opposite end portions thereof to cause the gases resulting from the burner when in operation to pass through the space formed between the two casings, and a protecting plate disposed between the casings opposite and in line with the burner.
- 10 6. A heater of the class described comprising inner and outer casings, end pieces closing the space formed between the cas-

ings, said end pieces being provided with outer laterally extending flanges engaging the outer casing and oppositely disposed inner flanges, one of the inner flanges of 30 each end piece engaging the inner casing, partitions disposed between said casings and forming independent compartments, a mixing chamber arranged on the exterior of the outer casing, a burner disposed within 35 the mixing chamber, an outlet pipe extending through the outer casing at a point on said casing opposite the burner, pipes fitted over the other inner flanges of said end pieces, and a pipe passing longitudinally 40 through the inner casing and having its opposite ends deflected laterally, one end of said pipe communicating with one compartment and the other end of said pipe communicating with the other compartment. 45

In testimony whereof we affix our signatures in presence of two witnesses.
